UNITED STATES PATENT OFFICE.

EDISON B. ELLIS AND JOSEPH M. HENDERSON, OF WAURIKA, OKLAHOMA.

STALK-CUTTER.

1,162,589.

Specification of Letters Patent. Patented Nov. 30, 1915.

Application filed February 10, 1915. Serial No. 7,359.

To all whom it may concern:

Be it known that we, EDISON B. ELLIS and JOSEPH M. HENDERSON, citizens of the United States, residing at Waurika, in the county of Jefferson and State of Oklahoma, have invented new and useful Improvements in Stalk-Cutters, of which the following is a specification.

This invention relates to stalk cutters, and it has for its object to produce a simple and efficient device of this character which may be produced at a very moderate expense.

A further object of the invention is to produce a simple and efficient stalk cutter which may be readily attached to the beam of an ordinary plow for the purpose of cutting stalks in advance of such plow, thereby facilitating and improving the operation of the plow.

20 A further object of the invention is to produce a simple and efficient stalk cutter comprising a revoluble element carrying blades or cutters and supporting means for the same including brackets adapted to be 25 clamped on a plow beam or the like, bearing members for the revoluble element, and resilient supporting devices.

With these and other ends in view which will readily appear as the nature of the invention is better understood, the same consists in the improved construction and novel arrangement and combination of parts which will be hereinafter fully described and particularly pointed out in the claims.

35 In the accompanying drawing has been illustrated a simple and preferred form of the invention, it being, however, understood that no limitation is necessarily made to the precise structural details therein exhibited, but that changes, alterations and 40 modifications within the scope of the claims may be resorted to when desired.

In the drawing,—Figure 1 is a side elevation of a stalk cutter constructed in accordance with the invention, and applied operatively to a plow beam. Fig. 2 is a front view of the same. Fig. 3 is a top plan view. Fig. 4 is a perspective detail view of one of the front brackets detached. Fig. 5 is a perspective detail view of one of the rear brackets detached. Fig. 6 is a perspective view of one of the resilient draft elements.

55 Corresponding parts in the several figures are denoted by like characters of reference.

The revoluble blade carrying element of

the improved stalk cutter comprises a shaft 15 having radially extending arms 17 on which blades 18 are bolted or otherwise secured. The ends of the shaft 15 are supported for rotation in eyes or bearings 19 formed at the lower ends of a pair of rods 20, the upper ends of which are guided through apertures 21 in a pair of arms or brackets 22 that extend in opposite directions from a plow beam 23 on which they are mounted, said brackets being provided at their inner ends with recesses 24 in which the beam 23 is snugly fitted, the brackets being also provided with lugs or ears 25 for the passage of fastening members, such as bolts 26, whereby the brackets are clamped securely on the beam. Springs S are coiled about the rods 20 between the brackets 22 and the bearings 19 to resist the thrust of said bearings in an upward direction.

The beam 23 is equipped with a second pair of brackets 27 which are located in advance of the first mentioned brackets 22 which they resemble in their general construction, being provided with beam engaging recesses 28 and with lugs or ears 29 for the passage of fastening bolts 30, whereby they are clamped on the beam. The outer extremities of the brackets 27 are flattened to provide seats 31 on which flat springs 32 are secured by fastening members, such as bolts or screws 33. Each of the flat springs 32 is bent forwardly and downwardly with respect to the brackets with which it is connected and then downwardly and rearwardly so as to form a loop 34 lying in advance of the bracket with which it is connected. The lower rearward extremity of each spring 32 terminates in an eye 35 receiving a portion of the shaft 15 that lies between a bearing 19 and a hub 16. The flat springs 32 constitute draft elements whereby the revoluble blade carrying element is drawn forward when draft is applied to the beam, and said draft elements, being resilient, will be capable of yielding freely when the springs S are compressed by the weight of the beam.

In the operation of this device draft is applied to the plow beam, and the machine is drawn over the field with the result that the stalks will be engaged by the blades of the revoluble element and be thereby chopped into short pieces which may be readily plowed under. As the springs S are compressed and expanded the resilient draft ele-

ments 32 will yield freely to such movement without danger of breaking, this being largely due to the formation of said elements with the loop 34 at the forward end 5 of each.

- The general construction is very simple and inexpensive, and the improved device is found to be thoroughly effective for the purpose for which it is provided.
- 10 The invention in the foregoing has been described as being applied to the beam of an ordinary plow in connection with which it may be successfully and advantageously operated. It will be understood, however, 15 that the use of the invention is not limited in this respect, since the improved stalk chopping device might be attached to a tongue or draft member enabling it to be used independently or in connection with 20 implements of various descriptions.

Having thus described the invention, what is claimed as new, is:—

1. In a stalk cutting device, two pairs of brackets having means whereby they may be 25 clamped on a supporting beam to extend laterally therefrom in opposite directions, spring actuated rods guided through one pair of brackets and having bearings at their lower ends, a revoluble blade carrying element including a shaft supported in said 30 bearings, and resilient draft elements connecting portions of said shaft with the other pair of brackets.
2. In a stalk cutting device, two pairs of 35 brackets having means whereby they may be

clamped on a supporting beam to extend laterally therefrom in opposite directions, 40 spring actuated rods guided through one pair of brackets and having bearings at their lower ends, a revoluble blade carrying element including a shaft supported in said bearings, and flat springs having eyes engaging portions of the shaft, said springs being provided at their forward ends with loops terminally secured on the other 45 brackets.

3. The combination with a plow beam, of a stalk cutting device including two pairs of brackets provided at their inner ends with recesses engaging said beams and with means 50 whereby said brackets are clamped upon the plow beam, rods guided through one pair of brackets and having bearings at their lower ends, springs coiled on the rods between the bearings and the brackets, a revoluble blade 55 carrying element including a shaft supported in the bearings, and resilient draft elements connecting the shaft with the other pair of brackets, said last mentioned brackets being located in advance of the brackets 60 through which the shaft carrying rods are guided.

In testimony whereof we affix our signatures in presence of two witnesses.

EDISON B. ELLIS.
JOSEPH M. HENDERSON.
